HENRY G. VOIGHT, OF NEW HAVEN, CONNECTICUT.

ADJUSTABLE DOOR CONTROL.

Application filed September 12, 1921. Serial No. 500,045.

To all whom it may concern:

Be it known that I, HENRY G. VOIGHT, a citizen of the United States of America, residing at New Haven, Connecticut, have invented a new and useful Adjustable Door Control, of which the following is a specification.

My invention relates to a door control and is particularly adapted for the actuation of multiple sliding doors, including one so-called "fast" door and one or more so-called "slow" doors, such as are commonly used for elevator shafts.

A common type of sliding door control consists of a link pivoted to the slow door and a link pivoted to the fast door and to one end of the slow door link. The other end of the slow door link is pivoted to a third link at one end, while the other end of this third link is pivoted to a wall or similar support. This system of linkage forms a type of toggle mechanism whereby, when the toggle is broken, the two doors are actuated. A spring closer and check is usually, though not always, provided with such mechanism.

With such door control mechanism it is in many cases necessary to specially design the control mechanism for each separate door and door opening. The actual door opening often varies, due to variations in individual workmanship on the building. Likewise, the distance from the door opening to the abutment for the toggle mechanism varies. It is obvious that with the toggle mechanism in its straightened out or rigid position and the fixed end of the toggle pivoted to the wall, unless the toggle mechanism is designed for the particular door opening, the door may not be able to reach its completely closed position.

The pivot bracket on the slow door has usually been in the form of a plate fastened to the door and having a pivotal connection to one link of the toggle. Since individual doors often vary in width, the link mechanism of predetermined proportions would fail to bring the doors into proper relation when in extreme positions. It has therefore heretofore usually been necessary to determine the pivotal point on the slow door bracket for each particular door, or to have a supply of slow door brackets having various points for pivotal connection. It has also been proposed to make one of the toggle links, usually the one which is connected to the wall plate, adjustable in length. This procedure,

while admissible for very slight variations in the distance between the side of the door opening and the wall plate, is not satisfactory where the variation is relatively large, 60 since varying the length of this toggle link which is connected to the wall bracket will cause one of the doors to reach its extreme position before the other door, and consequently the full extent of the door opening 65 cannot be realized.

It is an object of my present invention to overcome to a large extent the difficulties above indicated, and to provide means whereby the door control mechanism may be made 70 and assembled at the factory, ready for application to the doors, with the assurance that when applied said doors will operate properly and will open and close as intended, thereby saving greatly in cost of manufacture and 75 installation.

Another object is to provide an adjustable mounting for the abutment end of the operating linkage.

Another object is to provide an adjustment or offset to compensate for doors of different thickness and position.

A further object is to obviate the necessity of determining the pivot point on a slow door bracket for each particular installation, and in place thereof to provide an adjustable slow door bracket, whereby the pivot point on the slow door may be adjusted and the slow door accurately positioned.

The above objects may be accomplished by 90 means of the mechanism herein disclosed.

In the drawings I have shown for illustrative purposes one preferred form of my invention.

Figure 1 is a top plan view of a door control embodying features of my invention and showing a pair of sliding doors in the closed position;

Fig. 2 is a fragmentary side view of the parts shown in Fig. 1;

Fig. 3 is an enlarged detail view of an improved slow door bracket; and

Fig. 4 is a detail perspective view of a wall plate and adjustable abutment plate.

5 indicates the so called "fast" door of a 105 pair of sliding doors. 6 indicates the so called "slow" door. No means of supporting these doors has been shown, since this type of door and supporting means therefor are well known in the art and need no specific description.

A link 7 is pivotally connected at 8 to the

fast door. A second link 9 is pivotally connected at 10 to the slow door, through the medium of arms 26—27 later described. 11 is a lever which is pivotally supported from 5 a wall at 12. The link 9 is pivoted to the link 7 at 13 and to the lever 11 at 14.

The pivot point 12 for the fixed end of the toggle system is adjustably mounted relatively to the supporting wall. In the specific disclosure I have shown a wall plate 15 having apertures 16 to receive means for securing the plate to a proper support or wall. 17 indicates an abutment plate. This plate may be provided with means, such as 15 the ears 18, 18, for forming the fixed pivot point 12. In the specific instance shown ears 19 have been provided for attachment of the lower end of a door closer and check 20. The piston rod of this door closer and 20 check is connected at 21 to an ear on the lever 11.

Suitable means, such as rods 22, 22 extend from the wall plate 15 and pass through suitable passages in the abutment plate 17. 25 These supporting rods 22 have been shown as threaded, and the abutment plate 17 is held on these rods, as by means of nuts 23, 24 on opposite sides of the plate and in screw threaded engagement with said rods. 30 It will be seen that by varying the positions of the nuts on the rods the abutment plate 17 may be secured in various adjusted positions to and fro for the purpose later described. In the specific instance shown 35 the abutment plate 17 has been shown as supported by two rods, but it should be understood that the number is immaterial so long as the plate is given substantial support.

In the form shown one end of the lever 11 40 is supported in alignment with one of the rods 22, and I have shown an aperture 25 in the lever to clear the end of one of the rods 22 when the lever is in the uppermost position.

45 Means for pivoting the slow door to the bracket at 10 in the form shown comprises arms 26, 27, coming together at their ends and connected with the link 9, as by means of the pin or bolt 28. A securing plate 29 50 is provided for each of the arms and may be secured to the edge of the slow door in any suitable manner, as by means of the screws 30. Supporting bars 31 are formed integrally with/or secured in any suitable 55 manner to each of the arms 26, 27, which bars are adjustably connected to the mounting plates 29, 29 to govern offset. In the form shown the bars 31 pass through suitable apertures in the plates 29, and means, such 60 as the set screws 32, 32, are provided to hold the pins in various positions of adjustment.

It is obvious that if the plates 29 are separated farther apart than shown in Fig. 2 the door section 6 would be moved to the 65 left with respect to the pivot 10. By this

means the position of the door section 6 relatively to the adjacent sections or the casing may be properly adjusted. It will thus be seen that the proper relative positions of the doors 5, 6 may be accurately determined by simply spreading the arms 26, 27 relatively to each other to the proper degree, until the proper positions of the doors have been found. So, also, this arrangement makes it possible to adjust the 75 linkage to doors adapted to different widths of openings.

The operation is as follows:

When the toggle is broken, as by means of drawing down on the handle 35, the link 80 mechanism will assume, in the extreme open-door position, the position shown in dotted lines in Fig. 2, and both doors will be fully drawn back so as to overstand one another. If a door-closing spring is provided in the member 20, this spring will be stressed during the opening movement. If now the doors be released, the spring will draw downwardly on the lever 11 and the doors will be moved back to the closed position shown in full lines in Fig. 2.

It will be seen that by the provision of the adjustable abutment plate 17 the complete door-operating mechanisms may be assembled in the factory, and when installed 95 may be easily adjusted to overcome any slight errors such as usually found in buildings constructed to receive such door-control apparatus. It will also be seen that the means for adjusting the pivot point on the slow 100 door will permit variations in the sizes of individual doors to be compensated for, which adjustment of the bars 31, 31, will compensate for differences in offset. It will also be noted that all of these various 105 adjustments may be made without disturbing the effective centers of the toggle linkage.

While I have gone into great detail in disclosing specific forms of my invention, I do not wish to be limited thereto, for obviously many changes may be made within the scope of the invention as defined in the appended claims.

I claim:

1. In a door control for sliding doors, the 11 combination with a fast and slow door, of a link pivoted to the fast door, a second link pivoted to the slow door and to said first-mentioned link, and a lever pivoted to the link on the slow door and to a rigid abutment, resilient means for moving the links in one direction, and means for adjusting the pivot point on said rigid abutment whereby said link mechanism will be bodily 12 adjusted to and fro.

2. In a device of the character described, link mechanism for attachment to a door, a rigid abutment member connected to said link mechanism, and means for shifting said rigid abutment member to and fro to various 13

positions for determining the limit of travel of the door in its closing direction.

3. In a device of the character described, a toggle link mechanism adapted to be pivoted to a door, a rigid abutment member, said toggle mechanism being pivoted to said rigid abutment, and means for adjusting said rigid abutment member to various positions whereby the limit of travel of a door 10 operated by the toggle mechanism may be adjusted.

4. In a device of the character described, mechanism for actuating a sliding door, a fixed wall plate, a rigid abutment plate 15 mounted on said fixed wall plate, said actuating mechanism being pivoted to said rigid abutment, and means for adjusting the rigid abutment relatively to the fixed wall plate whereby the limit of travel of the door operated by said mechanism may be varied to suit existing conditions in building constructions.

5. In a device of the character described, toggle link mechanism for moving two sliding doors at different speeds including a rigid abutment member, said mechanism being connected to said abutment member at one end, and means for adjusting said abutment member to various positions whereby 20 the limit of movement of the doors operated by said mechanism may be varied at will.

6. In a device of the character described, toggle link mechanism for moving a door, and means for securing a pivot to said door, 25 said means being adjustable to vary the position of said pivot relatively to said door, said mechanism being connected to said pivot and closer mechanism associated with said link mechanism and cooperating therewith in all different positions of adjustment of said pivot.

7. In a device of the character described, link mechanism for moving a door, and an arm to be attached to a door and pivotally 45 connected with said mechanism, said arm being mounted on the door and adjustable to vary the position of said pivotal connection transversely of the door.

8. In a device of the character described, link mechanism for moving a door, and an arm to be attached to a door and pivotally 50 connected with said mechanism, said arm being mounted on the door and adjustable to vary the position of said pivotal connection toward and away from the door.

9. In a device of the character described, means for actuating a door, and a pair of arms on said door and pivotally connected to said door-actuating mechanism, said arms 60 being adjustable to vary the position of the pivotal connection of said arms to the mechanism in a direction transverse of the door.

10. In a device of the character described,

means for actuating a door, and a pair of arms on said door and pivotally connected 65 to said door-actuating mechanism, said arms being adjustable to vary the position of the pivotal connection of said arms to the mechanism in a direction toward and away from the door.

11. As an article of manufacture, an abutment member for connection to a door-operating mechanism, a support for said member, and means for adjusting said abutment member relatively to said support.

12. As an article of manufacture, an abutment for a door-operating mechanism, comprising a wall plate, an abutment plate connected to said wall plate, and means for varying the position of said abutment 80 plate relatively to said wall plate.

13. As an article of manufacture, an abutment mechanism for door-actuating means, comprising an abutment plate having means for pivotal attachment to a door-actuating 85 mechanism and having means for pivotally connecting a door closer, and means for adjusting said abutment plate relatively to its support.

14. As an article of manufacture, a wall 90 plate, an abutment plate, and means for adjustably securing said abutment plate in various adjusted positions relatively to said wall plate, said abutment plate having means for attachment to a door-actuating 95 mechanism and to a door check.

15. As an article of manufacture, a bracket for pivotal attachment to a door-actuating mechanism, comprising an arm for attachment to a door, and means for adjusting 100 said arm relatively to said door to vary the position of said pivotal attachment relatively to said door.

16. As an article of manufacture, a bracket for attachment to a door and for attachment to door-actuating mechanism, comprising a pair of arms, and means for attaching said arms to a door, said means being adjustable relatively to said arms.

17. As an article of manufacture, a bracket for attachment to a door and for pivotal connection to door-actuating mechanism, comprising an arm, a plate for attachment to a door, said arm being adjustably connected to said plate, and means for securing said arm in various positions of adjustment relatively to said plate.

18. As an article of manufacture, an arm for pivotal connection to door-actuating mechanism, a plate for attachment to a door, 120 means connecting said arm and said door, and means for holding said connecting means in various positions of adjustment whereby the arm and plate may be adjusted relatively to each other.

HENRY G. VOIGHT.
